UNITED STATES PATENT OFFICE.

GOTTFRIED WESTPHAL, OF GUTTENBERG, NEW JERSEY, ASSIGNOR TO DAVID SHAPIRO AND MEYER ARONSON, OF NEW YORK, N. Y., COPARTNERS DOING BUSINESS UNDER THE FIRM-NAME OF SHAPIRO & ARONSON.

DESIGN FOR A GAS AND ELECTRIC FIXTURE.

51,160.

Specification for Design.

Patented Aug. 14, 1917.

Application filed October 9, 1916. Serial No. 124,745. Term of patent 3½ years.

To all whom it may concern:

Be it known that I, GOTTFRIED WESTPHAL, a citizen of the United States, residing in Guttenberg, in the county of Hudson and State of New Jersey, have invented a new, original, and ornamental Design for Gas and Electric Fixtures, of which the following is a specification, reference being had to the accompanying drawing, forming a part of the same.

The present invention relates to an ornamental design for gas and electric fixtures.

In the drawing, Figure 1 shows an electric fixture, the various parts of which embody the design.

Fig. 2 is an enlarged detail of one of the design motifs.

Fig. 3 is an enlarged detail of another of the design motifs.

The fixture shown embodies a shower pan *a*, to which has been applied both of the motifs of my design, the motif *b*, being arranged in the form of a circle near the periphery and the motif *c*, also in the form

of a circle, disposed centrally of and concentrically within the motif *b*.

The fixture shown in the drawing also embodies a socket cover *d*, and has applied thereto both motifs of the design, motif *b*, being in the form of a band surrounding the outer surface and immediately above and adjacent to the motif *b*, is the motif *c*, in the form of a band.

The fixture shown in the drawing also embodies a shade *e*, to which has been applied both motifs of the design, the motif *b*, in the form of a band near the lower end of the shade and the motif *c*, in the form of a band near the upper end of the shade.

The fixture also embodies a canopy *f*, to which is applied the motif *b* of the design, upon the under surface of the flange *g*.

What I claim and desire to secure by Letters Patent, is:

The ornamental design for a gas and electric fixture as shown and described.

GOTTFRIED WESTPHAL.
